(57) **CLAIM**

The ornamental design for a load testing tension beam apparatus as shown and described.

DESCRIPTION

FIG. 1 depicts a front perspective view of the load testing tension beam apparatus of the present invention.

FIG. 2 depicts a first side elevation view of the load testing tension beam apparatus depicted in FIG. 1.

FIG. 3 depicts a top view of the load testing tension beam apparatus depicted in FIGS. 1 and 2.

FIG. 4 depicts a bottom view of the load testing tension beam apparatus depicted in FIGS. 1 through 3.

FIG. 5 depicts an end view of the load testing tension beam apparatus depicted in FIGS. 1 through 4; and,

FIG. 6 depicts a sectional view of the load testing tension beam apparatus depicted in FIGS. 1 through 5, along line 6-6 depicted in FIG. 2.

1 Claim, 2 Drawing Sheets
